United States Patent Office.

SIDNEY E. ALLEN, OF COMPANY SHOPS, NORTH CAROLINA.

Letters Patent No. 90,418, dated May 25, 1869.

POCKET-CASE FOR RAILROAD-SCHEDULES.

The Schedule referred to in these Letters Patent and making part of the same.

To all whom it may concern:

Be it known that I, SIDNEY E. ALLEN, of Company Shops, in the county of Alamana, and State of North Carolina, have invented a new and useful Improvement in Railroad-Schedules, &c.; and I do hereby declare that the following is a full, clear, and exact description thereof, which will enable others skilled in the art to make and use the same, reference being had to the accompanying drawings, forming part of this specification.

This invention relates to a new and useful improvement for facilitating the transaction of business on railroads and at railroad-stations, whereby much time and trouble are saved; and consists in arranging in a compact manner a list of stations on any railroad, a passenger and freight-tariff and time-table, with classification of freight enclosed in separate compartments, in a case of convenient and novel construction, as will be hereinafter more fully described.

In the accompanying plate of drawings—

Figure 1 represents the case open, showing a portion of the contents, the method of their arrangement, and manner of constructing the case.

Figure 2 represents the case open in another position, the two figures being in perspective.

Figure 3 is a cross-section through the case and its contents.

Similar letters of reference indicate corresponding parts.

A is the case, which is made in sections, or compartments, hinged or pivoted together, and consists of five sections, more or less, one of which contains a schedule of mail-stations on the road, while on the back of the adjacent section is a time-table for mail and freight-trains. Another compartment, or section, contains the list of stations, with the passenger-tariff. Another contains the classification of freight.

The lists of stations are on printed slips of paper, pasted in the bottoms of the compartment, while the time-tables and tariffs of freight and passengers are on separate slips for each station. The heading of each slip corresponds with and is placed opposite the list of stations. All the tariff-slips are clasped together and fastened to the case at their bottom ends, as seen at B B in the drawing. B B also shows the manner of their arrangement.

The classification of freight is contained in one of the sections, and is more in the book-form.

With the schedules, tariffs, time-tables, and freight-classifications, thus arranged and placed in their opposite sections, or compartments in the folding case, all the information in reference to the general business of a railroad may readily be carried in the pocket.

The cross-section, fig. 3; shows the case as folded up, but it will be seen that there is a great deal of spare or waste room.

A case of proper size for containing all the information required and mentioned above, will not exceed, say, five inches in length and about one inch in cross-section each way, so that the same may be carried and always be at the command of railroad-agents, thus greatly facilitating the transaction of railroad-business.

Having thus described my invention,

I claim as new, and desire to secure by Letters Patent—

The case A, composed of several sections, hinged together, and constructed and arranged substantially as and for the purpose specified.

SIDNEY E. ALLEN.
